UNITED STATES PATENT OFFICE

2,571,140

CONTINUOUS TYPE LASTING MACHINE

Jacob S. Kamborian, West Newton, Mass.

Application December 20, 1947, Serial No. 792,913

18 Claims. (Cl. 12—1)

1

This invention pertains to shoe lasting machines, more especially to lasting machines of the continuous-lasting type, and in particular to certain improvements in means for wiping-in and setting the work in lasted-in condition.

Among the objects of the invention are to provide improved means for wiping-in the upper by a continuous uninterrupted action and in such a way that the upper is laid smoothly over upon the insole, not only at the shank and forepart but also at the ends of the shoe; and to provide improved means for setting the wiped-in upper material so that it retains its position and does not draw back when the in-wiping operation ceases. Other and further objects and advantages of the invention will be pointed out in the following more detailed description and by reference to the accompanying drawings wherein

Fig. 1 is a fragmentary side elevation of a lasting machine embodying the present invention;

Fig. 2 is a fragmentary front elevation of the machine illustrated in Fig. 1;

Fig. 3 is a fragmentary front elevation, to larger scale, showing a relative position of the rolls, wiper and heating means;

Fig. 4 is a fragmentary side elevation, omitting certain parts, showing the relative positions of the feed rolls and stationary wiper;

Fig. 5 is a fragmentary horizontal section substantially on the line 5—5 of Fig. 1 but to larger scale; and

Figs. 6 to 10, inclusive, are diagrammatic elevations, illustrative of the way in which a shoe may be lasted by the use of the apparatus herein disclosed.

The present invention relates to improvements in certain features of a lasting machine of the general type disclosed in the patent to Kamborian, No. 2,251,285, dated August 5, 1941, and these improvements are here illustrated as embodied in a machine having some of the characteristics of and which functions in the same general way as the machine of said patent.

The machine herein illustrated comprises a base 1, preferably a hollow column housing a motor 2 and supporting the head or frame 3 which is provided with spaced bearings 4 and 5, respectively, for a horizontal shaft 6. A pulley 7, fixed to the rear end of the shaft 6, is embraced by a belt 8 which is driven by a pulley 9 on a shaft 10 turning in bearing brackets 11 and 12 projecting from the left-hand side of the frame 3. Another pulley 13, fixed to the rear end of the shaft 10, is driven by a belt 14 which

2

embraces a pulley 15 (Fig. 2) on the shaft of the motor 2.

A carriage 16 slides in guideways in the forward part of the frame 3 so as to move from front to rear and is urged rearwardly by springs (not shown). Treadle actuated means (not shown) may be provided for moving the carriage 16 forwardly in order to facilitate the introduction of the work between the feed rolls, hereinafter described, although the skilled operator is readily able to introduce the work between the feed rolls without first separating them by such forward movement of the carriage.

The carriage 16 has bearings for a rotatable shaft 17 (Fig. 4) whose axis is in a plane substantially parallel to the front of the machine, the axis of the shaft being inclined downwardly and to the left, that is to say, in the direction of advance of the work. As here illustrated, the axis of the shaft makes an angle of approximately 70° with the horizontal. A second shaft 18, whose axis is parallel with that of the shaft 17, is mounted in turn in bearings carried by the fixed frame 3. These shafts 17 and 18 are rotated by means of gearing (not shown) actuated by the shaft 6. Suitable means for driving the shafts 17 and 18 in opposite directions regardless of the position of the carriage 16 is disclosed in the aforesaid patent to Kamborian, to which reference may be had for a more detailed description of such a drive means.

To the lower end of the shaft 17 there is fixed a truncated upwardly tapering feed roll 19, and to the lower end of the shaft 18 there is fixed a truncated, downwardly tapering conical feed roll 20. Desirably these feed rolls have a taper of approximately 20°, that is to say, an angle of 20° between a plane tangent to the peripheral surface of the roll and the axis of the roll. A desirable and useful diameter for the larger end of the roll 19 is 0.795". These rolls are of complementary taper so that they make approximately a line contact when engaged. Their conical surfaces are preferably roughened, for example by knurling. Preferably this knurling is in the form of definite flutes, teeth or ribs, the teeth of the roll 19 sloping upwardly and to the left, as viewed from the front of the machine, and the teeth of the roll 20 sloping upwardly and to the right when similarly viewed.

A work hold-down 21 (Fig. 5), of crescent or shallow U-shape in plan view, is arranged so as partially to embrace the front roll 19. The under or work engaging surface of this hold-down 21 is preferably substantially at the level of

the lowest point in the bottom edge of the roll 19. A bracket 22, secured to the carriage 16 for vertical adjustment, supports this hold-down 21.

Preferably a vertically thin, fixed wiper, presser or guide member 23 (Fig. 4) is arranged to underlie the rear roll 20 and to extend forwardly substantially to the bite of the rolls 19 and 20. This fixed wiper bears against the marginal material of the upper at a point substantially in the vertical plane of the axes of the two rolls, and approximately at the level of the upper surface of the sole element S. The part 23 is carried by a bracket 24 secured to the fixed frame 3.

A vertically movable slide 25 (Fig. 1) is mounted in guides 26 carried by the left-hand side of the frame 3, the slide being urged downwardly by a spring (not shown) whose tension may be adjusted by a screw 28, the downward movement of the slide being limited by a stop screw 27. A bearing bracket 29 is attached to the lower edge of the slide 25 and is adjustable from front to rear, respectively, on the slide.

A wiper shaft 30 turns in an elongate bearing 31 forming a part of the bracket 29. An elongate rotary wiper 32 is fixed to the forward end of the shaft 30. This wiper has a truncated conical body portion of circular transverse section and has its larger end in the front. A helical rib 33 projects from the peripheral surface of the body portion of this rotary wiper. Preferably the edges of this rib are slightly rounded to avoid cutting the upper material.

The rear end of the shaft 30 is connected by a universal coupling (here shown as a form of Hooke's joint) to the forward end of the shaft 10, the universal coupling permitting vertical adjustment of the bearing 31 without interrupting the continuous drive of the wiper 32. For useful results the body of the wiper roll may be of the order of $1\frac{1}{8}$ " in length and of a diameter of approximately $\frac{1}{2}$ " at its forward end, and with a taper of approximately 5° , that is to say, a tangent plane to the periphery of the body makes an angle of 5° with the axis of the roll. These dimensions are given merely as examples and without limiting intent.

The wiper roll is preferably arranged with its axis substantially parallel to the vertical plane defined by the axes of the shafts 17 and 18, and is so located that its peripheral surface is substantially tangent (Fig. 5) to the lower portions of the inclined peripheries of the feed rolls 19 and 20. The forward end of the wiper roll 32 is so located as to overlap the bottom of the shoe being lasted, and is preferably at least as far forward as the tangent plane to the most forward point of the front roll 19, preferably extending from $\frac{1}{8}$ " to $\frac{1}{4}$ " forwardly of said plane. The helical rib 33 is of such pitch, here shown as left-handed, and the roll is rotated in such a direction, here shown as clockwise as viewed from the front, that the rib acts to urge the lasting margin of the shoe in a forward direction, that is to say, inwardly over the edge of the shoe bottom. Preferably, the axis of the wiper roll is inclined upwardly and forwardly, for example, the axis may incline to the horizontal at an angle substantially equal to the angle of taper of the roll.

A bracket 34 is adjustably secured to the forward part of the frame 3, and this bracket supports a downwardly directed nozzle 35 having its lower end spaced a short distance, for example $\frac{1}{4}$ ", above the plane of the upper surface of the roll 20 and with its axis substantially in the

transverse plane of the axis of the roll 19. This nozzle 35 (Fig. 1) is connected to a supply pipe 36 provided with a control valve 37 which is supplied with combustible gas (for example, illuminating gas) from a suitable source. Preferably, the nozzle 35 has air inlet openings 38 to insure proper combustion.

In operation, the gas issuing from the lower end of the nozzle 35 is ignited and produces a hot jet of flame indicated at F (Fig. 3). This flame jet F impinges upon the periphery of the wiper roll 32 and, due to the rotation of the roll, tends to follow the roll around, thus effectively heating the roll and to some degree acting directly upon the upper surface of the wiped-in lasting margin. In Figs. 6 to 10 inclusive the operation of lasting the platform cover or wrapper of a California type shoe is shown by way of example, but the apparatus of the present invention is intended to and is capable of lasting the uppers of conventional shoes, such as ordinary cement lasted shoes, and the operation, as illustrated in Figs. 6 to 10, is merely by way of example and without intent to limit the scope or utility of the invention, it being obvious that in lasting a conventional shoe the lasting margin of the upper will be entered between the rolls and subjected to up-drafting and in-wiping stress in substantially the same way as the platform cover or wrapper of the California shoe illustrated in Figs. 6 to 10.

In the operation of the machine the operator may, if desired, although it is unnecessary if he be sufficiently skilled, separate the feed rolls (Fig. 6) by the operation of the carriage-actuating treadle so as to permit a portion of the margin M of the platform cover to be entered between the rolls. The exposed bottom S of the shoe is brought into contact with the lower surface of the hold-down 21 (Fig. 7). The carriage 16 is then permitted to move backwardly, and the margin M is firmly gripped between the feed rolls 19 and 20 (Fig. 8). By reason of the shapes of these rolls and the inclination of their shafts in the direction of work advance, the rolls tend to progress the work from right to left, as viewed in Figs. 2 and 9, and at the same time they exert an upward component of stress which stretches the platform cover material snugly about the shoe bottom. As the marginal material, thus upwardly stressed by the rolls 19 and 20, escapes from between the rolls as the shoe advances, the marginal material M is engaged by the helical rib 33 (Fig. 10) of the rotating wiper 32 and is thereby stressed inwardly across the edge of the shoe bottom and is pressed firmly down against the exposed surface S of the shoe bottom. Assuming that the inner surface of the margin M and the exposed surface S of the shoe bottom have previously been coated with cement (Fig. 9), the operation of the wiper roll firmly presses the marginal material into adhesive engagement with the shoe bottom (Fig. 10). In accordance with the present invention as above described, the wiper roll 32 is heated, and the heat thus applied to the lasted-in marginal material tends to set the material in its wiped-in condition, it being well understood that the application of heat to leather tends to set it and cause it to become relatively hard and inelastic.

Furthermore, by the use of the heated wiper roll, it is possible to employ a cement for uniting the marginal material to the shoe bottom which only becomes adhesive in response to heat. Thus, cements of thermosetting or thermoplastic type

may be employed. Such cements have certain advantages, in particular they may not have any appreciable tackiness until exposed to heat. Thus, a coating of such a cement upon the marginal material and shoe bottom will not in any way interfere with the proper updrawing and in-wiping of the marginal material by the rolls 19 and 20 and wiper.

As illustrated in Fig. 3, the nozzle 35 is preferably arranged slightly to the right of the vertical plane of the axis of the wiper roll 32, and when so arranged the flame F tends to follow around the periphery of the roll 32 and into direct contact with the marginal material. Thus, the heat effect is accentuated, the marginal material being heated even before actual contact with the roll 32, thus assisting in a rapid activation of the cement if the latter be of the thermoplastic or thermosetting type. While an open flame has been suggested as the means for setting the wiper roll 32, it is obviously within the purview of the invention to heat the roll 32 by other means, for example by an electrical heating unit, steam or otherwise.

One desirable angle of inclination of the axes of the shafts 17 and 18 has been suggested, as well as a desirable taper for the feed rolls, but it is to be understood that the invention is not necessarily limited to the precise angles thus suggested, but that variations in these angles may be made within the scope of the invention, for example to accommodate work of different types. Although the machine herein described is referred to as a shoe lasting machine, it is capable of performing an operation similar to lasting upon other articles than shoes, for example, it is useful in performing certain upholstery operations, for instance, for drawing chair covers of leather, cloth, or the like over the frames of chair seats.

Thus, while for convenience, reference is herein made to a "shoe-lasting" machine; to a "last"; to a "platform cover"; and to the "lasting margin," these terms are employed in an illustrative sense and with reference to a chosen example, and are to be interpreted with the understanding and not as limitation upon the use of the invention nor upon the scope of the claims.

It is to be understood that the particular means for driving the operative parts of the machine are shown merely by way of example and that suitable modifications in the shapes or arrangements of parts and the substitution of equivalent parts for those shown are to be regarded within the scope of the invention as defined by the appended claims.

I claim:

1. In combination, in a machine for applying stretching stress to flexible sheet material, a rotary wiper having a tapering body of circular transverse section fixed at its smaller end to a supporting shaft, a helical work stressing rib projecting from the peripheral surface of its body portion, and means for heating the larger end portion of the wiper.

2. In combination, a lasting machine wiper, designed to lay the lasting margin of the shoe upper down upon the bottom of a sole member, said wiper being arranged to extend inwardly over said lasting margin and comprising an elongate body portion and a helical work-impelling element embracing the body portion, said work-impelling element being operative uninterruptedly to urge that portion of the lasting margin with which it is engaged in a direction substantially parallel to the axis of the helical element, the

body portion of the wiper tapering in diameter and having its smaller end at the rear, supporting means fixed to the smaller end of the wiper, and means for directing a hot fluid jet against said helical element.

3. A machine for lasting shoes which includes a pair of oppositely tapering frusto-conical rolls for gripping the lasting margin of the upper and for stretching the upper snugly about the last, an elongate, rotatable wiper having a helical work-impelling element operative uninterruptedly to engage said margin after it leaves said gripping rolls and uninterruptedly to impel the margin inwardly transversely of the edge of the last and to wipe the margin down upon the bottom of a sole carried by the last, a rotary drive shaft for turning the wiper, said shaft being coaxial with and rigidly connected to the rear end of the wiper, the shaft constituting the sole support for the wiper, the forward end of the wiper being free, and means for directing a jet of hot gaseous fluid against the forward free end portion of the wiper thereby to heat the wiper.

4. In a lasting machine of the kind having upper gripping means, including a rotating work-engaging roll, designed to stretch the upper snugly about the last and wherein the point of application of the stretching force is progressively shifted relative to the last along the periphery of the last and having a tapering rotating wiper provided with a helical work-engaging element whose point of effective engagement with the work is progressively shifted relative to the last concomitantly with the shift in the point at which the stretching force is applied, characterized in having means for directing a jet of flame against the peripheral surface of the wiper.

5. In a lasting machine of the kind having upper gripping means, including a rotating work-engaging roll, operative to stretch the upper snugly about the last and wherein the point of application of the stretching force is progressively shifted relative to the last along the periphery of the last, and having a tapering rotating wiper provided with a helical work-engaging element whose point of effective engagement with the work is progressively shifted relative to the last concomitantly with the shift in the point at which the stretching force is applied, characterized in having means for directing a jet of flame against the downwardly moving side of the rotating wiper.

6. In a machine for applying stretching stress to flexible sheet material, gripping means, including rotating, frusto-conical work-engaging rolls, designed to grip the margin of the sheet material and to stretch the latter and wherein the point of application of the stretching force is progressively shifted, and having a tapering rotating wiper provided with a helical work-engaging element whose point of effective engagement with the sheet material is progressively shifted concomitantly with the shift in the point at which the stretching force is applied, and means operative to apply heat to the sheet material as it is released by the gripping means.

7. A lasting machine having a rotary shaft which always rotates in the same direction and which carries a wiper operative to lay the lasting margin of the shoe upper down upon the bottom of a sole member, the wiper having a body of circular transverse section and a helical work-impelling element, the wiper extending across the edge of the sole member of the shoe being lasted and being operative progressively and un-

interruptedly to apply in-wiping stress to the lasting margin, the helical work-engaging element tapering in diameter with its smaller end at the rear, and a nozzle arranged to deliver a jet of heating fluid against the peripheral portion of the wiper which first engages the upper.

8. A machine for applying stretching stress to flexible sheet material, including front and rear, oppositely turning frusto-conical feed rolls whose axes are parallel and inclined downwardly in the direction of advance of the work, said rolls being operative to grip the sheet material and while stretching the latter concomitantly advancing the work uninterruptedly, a rotating helical wiping element operative uninterruptedly to engage the sheet material after it leaves the gripping means and uninterruptedly to stress said material in a direction approximately perpendicular to the direction of the stretching force exerted by the rolls, the axis of the wiping element being substantially parallel to the plane defined by the axes of said rolls, the helical element tapering in diameter with its smaller end at the rear, and means for directing a heating flame into the space between the rolls and the wiping element.

9. A machine for lasting shoes, said machine being of the kind which includes a pair of oppositely turning frusto-conical feed rolls whose axes are parallel and inclined downwardly in the direction of advance of the work, said rolls being operative to grip the lasting margin of the upper and while stretching the upper snugly about the last concomitantly to advance the shoe uninterruptedly, and having an axially elongate rotary wiper having a peripheral, helical work-impelling element, the wiper being so located that its work-impelling element engages the lasting margin as the latter escapes from the bite of the feed rolls and thereby urges that portion of the margin with which it is engaged in a forward direction substantially parallel to the axis of the wiper, a rotary drive shaft for turning the wiper, said shaft being coaxial with and rigidly secured to the rear end of the wiper and constituting the sole support for the wiper, the forward end of the wiper being free, and means for directing a jet of hot gaseous fluid against the forward free end portion of the wiper for heating the latter.

10. A machine for lasting shoes, said machine being of the kind which includes a pair of oppositely turning, frusto-conical gripper rolls whose axes are parallel and inclined downwardly in the direction of advance of the work, said rolls being operative to grip the lasting margin of the upper and while stretching the upper snugly about the last concomitantly to advance the shoe uninterruptedly and having wiping means operative to engage the lasting margin after the latter leaves the gripping means, and means for directing a flame against the wiping means for heating the latter said wiping means being operative uninterruptedly to impel the lasting margin as it escapes from the bite of the feed rolls inwardly across the edge of the shoe bottom.

11. A machine for lasting shoes, said machine being of the kind which includes a pair of oppositely turning frusto-conical rolls whose axes are parallel and inclined downwardly in the direction of advance of the work, said rolls being operative to grip the lasting margin of the upper and while stretching the upper snugly about the last concomitantly to advance the shoe uninterruptedly, and having wiping means operative uninterruptedly to urge the margin inwardly across

the edge of the sole member after the margin leaves the gripping means, and means for heating the margin of the sole immediately before it is operatively engaged by the wiping means.

12. A machine for lasting shoes, said machine being of the kind which includes front and rear, oppositely turning frusto-conical feed rolls whose axes are parallel and inclined downwardly in the direction of advance of the work, said rolls being operative to grip the lasting margin of the upper and while stretching the upper snugly about the last, concomitantly to advance the shoe uninterruptedly, heated wiping means for wiping in the lasting margin, and a work hold-down of substantially U-shape which partially embraces the front feed roll with its under surface substantially at the level of the lowest point of the front feed roll.

13. A machine for lasting shoes, said machine being of the kind which includes front and rear, oppositely turning frusto-conical rolls whose axes are parallel and inclined downwardly in the direction of advance of the work, said rolls being operative to grip the lasting margin of the upper and, while stretching the upper snugly about the last, concomitantly to advance the shoe uninterruptedly, constantly rotating means for wiping in the lasting margin, and a nozzle for directing heating fluid against the operative portion of said wiping means.

14. A machine for lasting shoes, said machine being of the kind which includes front and rear, oppositely turning frusto-conical rolls whose axes are parallel and inclined downwardly in the direction of advance of the work, said rolls being operative to grip the lasting margin of the upper and, while stretching the upper snugly about the last, concomitantly to advance the shoe uninterruptedly, means for uninterruptedly impelling the lasting margin as it escapes from between said rolls inwardly across the edge of the shoe bottom, and a nozzle for delivering a heating fluid medium against the marginal material as it is so impelled.

15. A machine for lasting shoes, said machine being of the kind which includes front and rear, oppositely turning frusto-conical rolls whose axes are parallel and inclined downwardly in the direction of advance of the work, said rolls being operative to grip the lasting margin of the upper and, while stretching the upper snugly about the last, concomitantly to advance the shoe uninterruptedly, a fixed member arranged to engage the marginal material at a point immediately below the bite of said rolls, constantly rotating wiping means operative to impel the marginal material, as it escapes from the bite of said rolls, inwardly across the edge of and to lay it down upon the shoe bottom, and heating means for activating heat responsive adhesive carried by the lasting margin thereby to make said adhesive tacky as it is laid down upon the shoe bottom by the wiping means.

16. A machine for applying stretching stress to flexible sheet material, including front and rear, oppositely turning frusto-conical rolls whose axes are parallel and inclined downwardly in the direction of advance of the work, said rolls being operative to grip the sheet material and, while stretching the latter, concomitantly to advance the work continuously and uninterruptedly, a wiper element operative to engage the sheet material as it leaves the gripping means and to stress said material in a direction approximately perpendicular to the direction of the stretching

force exerted by the rolls, means for actuating the wiper element, and means for directing a jet of hot fluid against the work-engaging portion of the wiper element.

17. A machine for lasting shoes, said machine being of the kind which includes front and rear, oppositely turning, oppositely tapering, frustoconical feed rolls whose axes are parallel and inclined downwardly in the direction of advance of the work, said rolls being operative to grip the lasting margin of the upper and while stretching the upper snugly about the last, concomitantly to advance the shoe continuously, means for directing a jet of hot gaseous fluid against said marginal material as it escapes from between the rolls, and means operative to work the heated marginal material inwardly over the last bottom.

18. A machine for applying stretching stress to flexible sheet material, including front and rear, oppositely turning, oppositely-tapering, frustoconical work-gripping, feed rolls whose axes are substantially parallel and inclined downwardly in the direction of the advance of the work, whereby the rolls exert an upward stress upon the material, the forward roll tapering upwardly and the rear roll tapering downwardly, an elongate

5
10
15

rotatable wiper, a rotary drive shaft for the wiper coaxial with the latter and rigidly secured to the wiper, said shaft constituting the sole support for the wiper, the forward end of the latter being free, means for heating the forward, free end portion of the wiper, a hold-down device to limit upward movement of the work in response to the upward stress exerted by the rolls, and means for rotating the wiper.
